UNITED STATES PATENT OFFICE

WALTER H. HALL, OF WINCHESTER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

WORK-POSITIONING DEVICE FOR WOOD-HEEL JACKS

Application filed January 4, 1928. Serial No. 244,530.

This invention relates to heel making machines and is illustrated as embodied in a wood heel turning machine of the type disclosed in United States Letters Patent No. 5 1,488,534, granted April 1, 1924, on application of Folsom, Vinton and Whitney.

Machines of this type are provided with two rotary cutters and a jack for holding a heel blank, the blank being swung past one cutter by the jack to make a cut around one side of the heel blank from breast to back and then past the other cutter to cut around the other side of the blank. It has been customary to clamp the heel blank in the jack by its top-lift and heel-seat surfaces and to gage it only by a gage at its breast surface, since the lateral and rear surfaces of the blank were to be trimmed by the cutter.

20 The invention of A. F. Cook disclosed in his application Serial No. 274, 583, filed May 2, 1928, provided, in addition to the usual breast gage, a side gage arranged to contact with a lateral face of a wood heel blank and 25 removable from operative position after the blank had been gaged to permit the trimming cutter to form the lateral heel surface on the blank, the gage being moved from operative to inoperative position by a handle, thus insuring proper relationship between the side 30 and breast surfaces formed on the blank. It is an object of this invention to provide a still further improved construction of the type provided by the invention of Cook. To

35 this end I have provided an organization comprising, as illustrated, a side gage sliding from operative to inoperative position, thus simplifying to a considerable degree the construction and operation of the machine. 40 Advantageously also, the handle used to operate the gage is used also to clamp the heel blank and to turn the jack.

The specific construction of the jack shown 45 herein is not claimed in this application but forms the subject matter of a divisional application Serial No. 355,221, filed by me April 15, 1929.

50 My invention further relates to arrangements and combinations of parts which

will be hereinafter described and more particularly set forth in the appended claims.

A preferred form of the invention is shown in the drawings in which

Fig. 1 is a side elevation of my improved 55 jack and gauge;

Fig. 2 is a sectional plan view, taken along the line 2—2 in Fig. 1;

Figs. 3 and 4 are views similar to Figs. 1 and 2, but showing the parts in a different position; and

Fig. 5 is a detail sectional view, taken along the line 5—5 in Fig. 3.

Referring to the drawings, my improved jack comprises a frame member 10, secured to the upper end of a supporting shaft 11 and having swinging movement about the axis of said shaft. A heel blank support 12 is pivoted at 13 to the member 10. The support 12 has a bearing portion 14 engaging a 65 cam member 15 and angularly movably thereby as the jack is swung about the axis of the shaft 11.

A frame member 17 is secured to the support 12 and extends upward therefrom.

The heel blank B rests on a serrated plate 20 (Fig. 2) on the support 12, and the upper surface of the heel blank is engaged by a clamping bar 21 having a cross pin or stud 22 loosely pivoted in a slot 23 in the frame member 17.

A hand lever 25 is pivoted at 26 on a lever 27, which in turn is pivoted at 28 to the frame member 17. A cam roll 30 on the hand lever 25 engages the upper surface of the clamping bar 21 as the handle is swung downward and forces the clamping bar against the upper surface of the heel blank B.

An adjusting screw 32 is threaded in the upper end of the frame member 17 and acts as an adjustable abutment to limit upward movement of the lever arm 27. The screw 32 thus constitutes means for controlling and adjusting the pressure on the heel blank B.

A guide member 40 is secured to the side of the support 12 and is provided with a guide-way 41 (Fig. 2) for a guide bar 42 having a side gauge block 43 secured thereto by screws 44 extending through slots 45. The block 43 is thus laterally adjustable toward or from 100

the side of the heel blank, which is indicated in broken lines at B' in Fig. 2.

A bell crank 47 (Fig. 1) is pivoted at 48 on the support 12, and one arm of the bell crank 47 extends upward through a slot or opening 49 (Fig. 2) in the guide bar 42, and the other arm of the bell crank is connected to the lower end of a link 50. The link 50 is provided with an elongated slot 51 toward its upper end, through which extends a stud 52 in the outer end of an arm 53 pivoted at 54 on the hand lever 25. The arm 53 has a segmental slot 56 through which extends a clamping screw 57 threaded in the hand lever 25. The position of the stud 52 may thus be conveniently adjusted relative to the hand lever 25 by loosening the screw 51 and swinging the arm 53 on its pivot 54. A molding cutter is indicated diagrammatically at C (Fig. 1), and a usual breast gage at 60, (Figs. 2 and 3).

Having described the details of construction of my improved jack, and side gauge therefor, the method of operation will be readily apparent. When the jack is open to permit removal and replacement of heel blanks, the hand lever 25 is in the raised position indicated in Fig. 1 and the bell crank 47 is moved to advance the side gauge block 43 to operative position. This movement takes place as the hand lever 25 approaches its uppermost position, in which position the pressure of the cam roll 30 on the clamping bar 21 is also released.

The finished heel blank B may then be removed and a new blank B' may be inserted and accurately positioned laterally by the gauge block 43. The usual breast gage 60 (Fig. 2) at the same time engages the front edge of the blank, which is thus accurately positioned in two directions.

The hand lever 25 is then moved downward to the position indicated in Fig. 3 and as the lever approaches its lower limit of travel, the gauge block 43 is slid back to the position indicated in Figs. 3 and 4. It will be noted that the lost motion connection allows the gauge block to remain in forward or operative position until the clamping bar 21 engages the blank B', thus holding the same from displacement as the gauge block 43 is withdrawn.

The handle 25 is then used to swing the jack, with its clamped heel blank, around against the cutter C to form a lateral and rear surface on the blank, as will be understood from the Letters Patent referred to.

By the use of my improved side gauge, the blocks may be more accurately positioned and consequently smaller blocks may be used, as less clearance at the sides is necessary than in the previous practice.

Having thus described my invention and the advantages thereof, I do not wish to be limited to the details herein disclosed other-

wise than as set forth in the claims, but what I claim is:—

1. In a wood heel jack, a heel blank support, means to open and close said jack relative to said support, and a side gauge for a heel blank on said support, said gauge being slidable forward to operative position adjacent said support and being slidable rearward to a position permitting unobstructed cutting operations on the sides of the heel blank. 75

2. In a wood heel jack, a heel blank support, actuating means to open and close said jack relative to said support, a side gauge for a heel blank on said support, and a connection from said actuating means to said gauge 80 rectilinearly effective to move said gauge forward and rearward as said actuating means is moved to open and close said jack, said connection including a lost motion element, whereby said gauge will be moved in each 85 direction as the actuating means approaches its limit of travel in the corresponding direction.

3. In a wood heel jack, a heel blank support, actuating means to open and close said jack relative to said support, a side gauge for a heel blank on said support, a connection from said actuating means to said gauge effective to move said gauge forward and rearward as said jack is opened and closed, and 95 means to adjust the forward limit of travel of said gauge.

4. In a wood heel jack, a heel blank support, a hand lever to open and close said jack relative to said support, a side gauge for a heel blank on said support, and a connection from said hand lever to said gauge effective to move said gauge rectilinearly forward and rearward as said hand lever is moved to open and close said jack. 100

In testimony whereof I have hereunto affixed my signature.

WALTER H. HALL.

CERTIFICATE OF CORRECTION.

Patent No. 1,762,296.

Granted June 10, 1930, to

WALTER H. HALL.

It is hereby certified that error appears in the printed specification of the above numbered patent requiring correction as follows: Page 2, line 81, claim 2, strike out the word "rectilinearly" and insert same to follow "gauge" same line and claim; and that the said Letters Patent should be read with this correction therein that the same may conform to the record of the case in the Patent Office.

Signed and sealed this 6th day of January, A. D. 1931.

**M. J. Moore,
Acting Commissioner of Patents.**
